VALVE OPERATING MECHANISM

Edward J. Fitz, Fairfield, Conn., assignor to Jenkins Bros., New York, N. Y., a corporation of New Jersey

Application February 17, 1942, Serial No. 431,304

8 Claims. (Cl. 74—407)

This invention relates to devices for opening and closing valves, and more particularly to valve operating mechanisms of the power actuated, automatically controlled type wherein manually operable means are also provided for opening or closing the valves in an emergency.

Although valve operators of the same general character as that of the present invention have been known to the art for some time, these prior devices have not proven entirely satisfactory from a practical standpoint because of various difficulties inherent in the particular mechanical arrangements proposed.

It is therefore one of the objects of the present invention to provide a valve operating mechanism of new and improved construction which will ensure efficient and dependable operation under all conditions and will be free from the defects of similar devices hitherto known.

Another object of the invention is to provide a valve operator of the type normally driven by electrical or hydraulic energy with novel manually operable means for opening and closing the valve in an emergency.

A further object is to provide manually operable means of novel construction for actuating a motor driven valve which automatically disconnects the motor from the valve during the cycle of manual operation and automatically re-establishes the motor driving connection when application of the manual operating force ceases.

Still another object of this invention is to provide an improved valve operating mechanism of the character described which is structurally simple, economical to manufacture, durable, and dependable in operation.

These and other objects will appear more fully upon consideration of the detailed description of the embodiments of the invention which follows. Although only two specific forms of valve operator have been described and illustrated in the accompanying drawings, it is to be expressly understood that these drawings are for purposes of illustration only and are not to be construed as defining the limits of the invention, reference being had for the latter purpose to the appended claims.

In the accompanying drawings, wherein like reference characters indicate like parts throughout the several views:

Fig. 1 is a side elevation, with certain parts shown in section, of one form of electrically driven valve actuating mechanism embodying the novel manually operable means of the present invention, the elements of the manual operating means being shown in their normal, inoperative positions;

Fig. 2 is an end view of the mechanism of Fig. 1, as seen from the right in the latter figure;

Fig. 3 is a sectional view taken substantially

on line 3—3 in Fig. 1 showing the form of connection between the motor actuated, main driving shaft and the valve gear;

Fig. 4 is a plan view of the sliding cam sleeve 5 of the manually actuatable emergency operating means;

Fig. 5 is a fragmentary sectional view of a portion of the manually actuatable operating means of Fig. 1 showing the elements thereof in operative position;

Fig. 6 is a view similar to Fig. 1 of a hydraulically actuated valve operator embodying a modified form of manual operating means constructed in accordance with the invention; and

Fig. 7 is a schematic diagram of a hydraulic valve operating circuit illustrating the advantage of the improved manual operating means of the present invention over the conventional form of such means wherein the hydraulic motor is not disconnected during manual actuation of the valve.

Referring first to Figs. 1, 2 and 3, the embodiment of the invention illustrated therein comprises an electric driving motor and its associated power transmission and control mechanism for normally operating a valve gear (the valve itself having been omitted from the drawings in the interest of simplicity), and manually actuatable means normally inoperative but operable in the event of an emergency for opening and closing the valve.

As shown, the main drive shaft 10 of the device is journaled in suitable bearing bushings carried by a two part oil-tight housing 11, and is adapted to be driven by an electric motor 12 through suitable gearing such as a worm gear 13. The driving connection between the worm gear 13 and the shaft 10 may be of any desired character, and may embody a torque responsive mechanism of the type disclosed in application Serial No. 201,594, filed April 12, 1938, of which this is a continuation in part. For purposes of illustration, it may be assumed that the structure indicated in Figs. 1 and 2 is the same as that shown in the corresponding views of said earlier application, including both torque responsive and travel limit means which extend through the housing 11 into a switch box 14 and serve to automatically open the circuit of motor 12 whenever the resistance to rotation of shaft 10 exceeds a predetermined value or the valve reaches a predetermined point in its movement in one direction or the other.

Shaft 10 is reduced in diameter at 15, and secured thereto for rotation therewith as by key 16 is driving collar 17 which, as shown best in Fig. 3, is provided at one point on its periphery with an outwardly extending lug or finger 18. Mounted for rotation upon shaft 10 and recessed to receive driving collar 17 is valve drive gear

19 which has a hub 20 extending outwardly along shaft 10. Slidably supported upon hub 20 is a sleeve 21, the inner end of which has an outwardly turned flange notched at one point on its periphery to receive and lockingly engage with a pin 22 which is slidably mounted in gear 19. Pin 22 normally extends inwardly into the recessed portion of gear 19 sufficiently to engage the finger 18 of driving collar 17 in the manner indicated in Fig. 3.

The outer end of sleeve 21 is recessed as at 23 to receive a spring 24 the inner end of which normally urges the sleeve to the left as seen in Fig. 1 so as to bring the flanged end thereof into contact with drive gear 19, the outer end of spring 24 abutting against spring rest 25 mounted in a recessed portion 26 of hub 20 and held in position by cap 27 which is suitably secured to hub 20 of gear 19, as by a set screw 28. Mounted for rotation on sleeve 21 is a liner 29 upon which is mounted hub 30 of hand wheel 31, said liner and hub being secured together by a locking pin 32. Oil or grease may be admitted to this assembly through any suitable lubricating fitting 33.

Hub 30 of hand wheel 31 is enlarged and recessed as indicated at 34 to provide a housing for the mechanism by which the hand wheel may be coupled to the valve gear 19 for manual operation. As shown, there is mounted in recessed portion 34 a plunger 35 urged outwardly by spring 36. A glass cover 37 held beneath clips 38 (Fig. 2) normally retains plunger 35 in its inward position (Fig. 1) against the action of spring 36. Plunger 35 is circumferentially recessed at 39 to receive finger 40 of cam member 41 which is designed to rotate about pin 42 and to engage cam slot 43 of sleeve 21 when the manually actuatable means are in operative position (see Figs. 4 and 5).

The element 44 is a travel limit switch shaft which is rotatably carried within the longitudinal center bore 45 of shaft 10, is fixed at one end to the cap 27 by the pin 46 and extends all the way into the switch box 14 to actuate the travel limit switches.

During normal valve actuation, the shaft 10 is driven by the motor 12 through the worm gear 13 and associated torque responsive mechanism, rotation of the shaft 10 also rotating driving collar 17, and, through the finger 18 and pin 22, valve gear 19. Rotation of valve gear 19 also acts through pin 22 to rotate sleeve 21 within the liner 29 and hub 30 of hand wheel 31, these elements being disconnected due to the fact that the cam member 41 is in its normal disengaged position. The movement of valve gear 19 is also transmitted through hub 20 and set screw 28 to cap 27 which in turn rotates travel limit switch shaft 44 through pin 46. When the valve reaches the desired limit of its movement, the circuit of the motor 12 is automatically opened by either the torque responsive or the travel limit switch mechanism in the manner disclosed in the aforesaid application. Serial No. 201,594.

If, for any reason, the electrical means provided to operate the device should fail, the manually actuatable means shown in Figs. 1-5 may be used. To place the hand wheel 31 in driving relation with valve gear 19, glass 37 is broken by any suitable means, as by a hammer 47 clipped to the hand wheel for this purpose, so as to permit the plunger 35 to be forced to the right in Fig. 1 by spring 36. This outward movement of the plunger 35 rotates cam member 41

in a counter-clockwise direction about pin 42 so as to urge the end of the cam into the slot 43 of sleeve 21, as shown in Fig. 5. If slot 43 is not opposite cam 41 when the plunger 35 is released, hand wheel 31 may be rotated in either direction until the cam registers with and enters the slot. When the elements occupy the positions shown in Fig. 5, the hand wheel 31 may be rotated in the proper direction to open or close the valve, as desired, the hand wheel driving the valve gear 19 through cam 41, slot 43, sleeve 21 and pin 22. Due to the shape of cam slot 43 as shown in Fig. 4, initial rotation of hand wheel 31 and cam 41 in either direction after engagement of the cam and slot will cause the sleeve 21 to slide to the right in Fig. 1 against the action of spring 24 and to draw the pin 22 outwardly to such an extent that, when gear 19 is rotated thereafter, the pin will not engage the finger 18 of driving collar 17.

With this construction, the manually actuatable means may be operated without driving back through the transmission normally operated by the motor. At the same time, however, it will be noted that manual rotation of gear 19 also rotates shaft 44 as above described so that the limit switches are opened and closed appropriately and in such a manner that the switch mechanism will be in its correct position should the electrical actuating means thereafter be used to operate the valve.

When it is no longer necessary to use the manual operating means, plunger 35 may be pressed to the left in Fig. 1 against the action of spring 36, thereby rotating cam 41 clockwise about pin 42 and disengaging it from slot 43, and a suitable piece of glass placed under clips 38 (Fig. 2) to retain the plunger in its inward position. Spring 24 then slides sleeve 21 to the left which in turn moves pin 22 into position for contact with the driving finger 18.

Referring now to Figs. 6 and 7, there is shown in the former an adaptation of the manual operating means of the present invention to a valve operator of the hydraulic type, the latter figure illustrating a known form of hydraulic circuit for remotely controlling such devices and indicating one of the advantages of the present manual means in comparison with those heretofore in use. Aside from the fact that the hand wheel of the operator shown in Fig. 6 is permanently latched in operative connection with the valve drive gear, the modified structure is substantially the same as that of Figs. 1-5; in fact, many of the parts of the two devices may be so constructed as to be interchangeable.

In the embodiment illustrated, the main drive shaft 10 is permanently connected to and normally driven by a hydraulic motor 48 of any suitable construction which may be operated in either direction by oil or other fluid supplied thereto and delivered therefrom by a pair of conduits 49, only one of which is shown in Fig. 6. As is indicated in Fig. 7, the hydraulic motor is connected to the actuating fluid circuit by a three-way selector cock 50 so that the flow created by the pump 51 may either drive the motor in one direction or the other, or may by-pass the motor when the cock is in central or neutral position. With hydraulic valve operators of known construction wherein it is impossible to operate the valve manually without simultaneously actuating the rotor of the motor, the cock 50 must be turned to neutral position for manual operation in order to avoid the possibility of a hydraulic lock which

would occur should the cock occupy a position opposite to that corresponding to the desired direction of operation of the valve.

As in the case of the device of Figs. 1-5, shaft 10 has keyed thereto a driving collar 17 provided with an outwardly extending lug or finger 18 adapted to engage the pin 22 which is slidably mounted in the valve driving gear 19, and to thereby rotate the latter when the shaft 10 is driven by the motor 48. Valve gear 19 is permanently meshed with a driven gear 52 which is keyed to a hollow shaft 53 having an operative connection with the spindle 54 of the valve to be operated (indicated at 55 in Fig. 7). The valve drive gear 19 is also provided with a hub 20 extending outwardly along and surrounding shaft 10, on which hub is slidably supported a sleeve 21 having at its inner end an outwardly turned flange notched at one point on its periphery to receive and lockingly engage with the pin 22. The outer end of sleeve 21 is recessed at 23 to receive a spring 24 which normally urges the sleeve to the right as viewed in Fig. 6 so as to bring the pin 22 into position to engage the finger 18, the outer end of spring 24 abutting against a spring rest 25 which surrounds the outer end of hub 20 and is held in place by a cap 56 suitably secured to the outer reduced end 57 of shaft 10.

Mounted on the outer end of the sleeve 21, and capable of rotation relatively thereto, is a liner 29 which in turn supports the hub 58 of hand wheel 59, the hub 58 being fixed to the liner 29 by a locking pin 32. Instead of normally being free to spin relatively to the sleeve 21 and hub 20, as in the embodiment of Figs. 1-5, the hand wheel of Fig. 6 is adapted for permanent operative connection with the sleeve 21. Accordingly, in lieu of the plunger operated cam arrangement illustrated in Figs. 1-5, the hub 58 of hand wheel 59 is simply provided with an enlarged portion 60 in which is formed a radially extending opening 61 housing a cam finger 62, the inner end of the latter extending into the cam slot 43 of the sleeve 21.

The mode of operation of the device shown in Fig. 6 is the same as that previously described in connection with the embodiment of Figs. 1-5, except for the fact that the permanent projection of cam finger 62 into cam slot 43 renders the device ready for manual operation at all times without the necessity for first latching the hand wheel to the sleeve.

When the manual operating means of the present invention is thus applied to a hydraulically actuated valve operator, there is no movement of the rotor of the hydraulic motor when the valve is manually opened or closed. This being so, it is unnecessary to turn the selector cock to neutral position before manually operating the valve as must be done with the conventional type of operator in order to avoid a hydraulic lock at the remote control station in the event that the cock should inadvertently be turned to a position opposite to that corresponding to the direction in which the valve is being moved manually. This feature of the invention is diagrammatically indicated in Fig. 7 wherein the valve operator at the right-hand side of the diagram embodies manual actuating means of the automatic motor disconnecting type, while the one to the left employs a hand wheel which is permanently connected with the hydraulic motor. In the latter case, proper operation requires that the selector cock 50 be turned to neutral position so as to permit a closed circulation of the oil or other

fluid through the motor when the valve is manually actuated, whereas the device of the present invention enables operation by hand independently of the hydraulic motor and without causing any circulation of fluid.

There is thus provided by the present invention a valve opening and closing device of improved construction wherein are embodied novel means for manually actuating a valve operator of the normally electrically or hydraulically driven type which are so constructed as to be operable independently of the elements constituting the normal drive between the motor and valve gear and which automatically disconnect the motor from the valve gear during manual actuation of the valve. While only two specific forms of the invention have been described and illustrated in the accompanying drawings, it will be obvious that the invention is not limited to the exact structures shown but is capable of a variety of mechanical embodiments. Various changes, which will now suggest themselves to those skilled in the art, may be made in the form, details of construction and arrangement of the parts without departing from the spirit of the invention. Reference is therefore to be had to the appended claims for a definition of the limits of the invention.

What is claimed is:

1. In a device of the character described, the combination of a drive shaft, a driving gear rotatably mounted on said shaft, means for establishing a driving connection between said shaft and said gear, manually actuatable means for rotating said gear including a hand wheel, a member rotatable with, but movable axially relatively to, said gear, means for drivingly connecting said hand wheel and member so constructed and arranged as to permit a limited rotational movement of said hand wheel relatively to said member and to simultaneously produce an axial movement of the latter relatively to said gear, and means actuated by the axial movement of said member for disestablishing the driving connection between said shaft and said gear.
2. In a valve operator of the class described, the combination of a drive shaft, valve drive means rotatably mounted on said drive shaft, means for establishing a positive drive from said drive shaft to said valve drive means, manually actuatable means for operating said valve drive means including a hand wheel, a member rotatable with but movable axially relatively to said valve drive means, means for drivingly connecting said hand wheel and member including a cam groove and follower arrangement such that said hand wheel may be rotated relatively to said member through a limited distance to produce an axial movement of the latter with respect to said valve drive means, and means actuated by the axial movement of said member for rendering ineffective the drive-establishing means between said drive shaft and valve drive means.
3. In a valve operator of the class described, the combination of a drive shaft, valve drive means rotatably mounted on said drive shaft, means for establishing a positive drive from said drive shaft to said valve drive means including a pin carried by said valve drive means and normally engaged by a member rotatable with said drive shaft, a hand wheel, and means for operatively connecting said hand wheel with said valve drive means including an axially movable element having a cam groove formed therein, a cam follower member carried by said hand wheel

for engagement with said cam groove, said cam groove and follower member being so constructed and arranged that manual rotation of said hand wheel first produces a limited axial, non-rotational movement of said element and thereafter rotation of said element with said hand wheel, and means for transmitting the axial movement of said element to said pin to move the latter out of engagement with said member rotatable with the drive shaft, whereby the valve drive means may be rotated by said hand wheel without rotation of said drive shaft.

4. In a valve operator of the class described, the combination of a drive shaft, a valve drive gear having a hub rotatably mounted on said drive shaft, means for establishing a positive drive from said drive shaft to said gear including a driving member fixed to said shaft and a driven pin mounted in said gear for rotation therewith but capable of axial movement relatively thereto, said pin normally extending into the path of rotation of said driving member so as to be engaged and driven thereby, a hand wheel, and means for operatively connecting said hand wheel with said gear for manual actuation thereof including a sleeve member mounted on said gear hub for rotation therewith but capable of axial movement relatively thereto, a cam groove formed in said sleeve member, a cam follower member carried by said hand wheel for engagement with said cam groove, said cam groove and follower member being so constructed and arranged that manual rotation of said hand wheel first produces a limited axial, non-rotational movement of said sleeve member and thereafter rotation of said sleeve member with said hand wheel, and means for transmitting the axial movement of said sleeve member to said pin to move the latter out of the path of rotation of said driving member, whereby the valve drive gear may be rotated by said hand wheel without rotation of said drive shaft.

5. In a valve operator of the class described, the combination of a drive shaft, a valve drive gear rotatably mounted on said drive shaft, means for establishing a positive drive from said drive shaft to said gear, manually actuatable means for rotating said gear including a hand wheel normally disconnected from said gear, a member rotatable with but movable axially relatively to said gear, means for drivingly connecting said hand wheel and member including a cam groove and follower arrangement such that said hand wheel may be rotated relatively to said member through a limited distance to produce an axial movement of the latter with respect to said gear, and means actuated by the axial movement of said member for rendering ineffective the drive establishing means between said drive shaft and said gear.

6. In a valve operator of the class described, the combination of a drive shaft, a valve drive gear rotatably mounted on said drive shaft, means for establishing a positive drive from said drive shaft to said gear including a pin carried by said gear and normally engaged by a member rotatable with said drive shaft, a hand wheel normally disconnected from said gear, means for operatively connecting said hand wheel with said gear including an axially movable element having a cam groove formed therein, a cam follower

member carried by said hand wheel and normally retained out of engagement with said cam groove, means for engaging said cam follower member with said cam groove, said cam groove and follower member being so constructed and arranged that rotation of said hand wheel after engagement of said follower member with said groove first produces a limited axial, non-rotational movement of said element and thereafter rotation of said element with said hand wheel, and means for transmitting the axial movement of said element to said pin to move the latter out of engagement with said member rotatable with the drive shaft, whereby the valve drive gear may be rotated by said hand wheel without rotation of said drive shaft.

7. In a valve operator of the class described, the combination of a drive shaft, a valve drive gear having a hub rotatably mounted on said drive shaft, means for establishing a positive drive from said drive shaft to said gear including a driving member fixed to said shaft and a driven pin mounted in said gear for rotation therewith but capable of axial movement relative thereto, said pin normally extending into the path of rotation of said driving member so as to be engaged and driven thereby, a hand wheel normally disconnected from said gear, means for operatively connecting said hand wheel with said gear for manual actuation thereof including a sleeve member mounted on said gear hub for rotation therewith but capable of axial movement relatively thereto, a cam groove formed in said sleeve member, a cam follower member carried by said hand wheel normally retained out of engagement with said cam groove but movable into engagement with the latter when manual operation of the valve is desired, said cam groove and follower member being so constructed and arranged that rotation of said hand wheel after engagement of said follower member with said cam groove first produces a limited axial, non-rotational movement of said sleeve member and thereafter rotation of said sleeve member with said hand wheel, and means for transmitting the axial movement of said sleeve member to said pin to move the latter out of the path of rotation of said driving member, whereby the valve drive gear may be rotated by said hand wheel without rotation of said drive shaft.

8. In a valve operator of the class described, the combination of a drive shaft, a valve drive gear rotatably mounted on said drive shaft, means for establishing a driving connection between said shaft and said gear, manually actuatable means for rotating said gear including a hand wheel, means for operatively connecting said hand wheel with said gear including an axially movable element having a cam groove formed therein, a cam follower member carried by said hand wheel and normally in engagement with said cam groove, said cam groove and follower member being so constructed and arranged that manual rotation of said hand wheel first produces a limited axial, non-rotational movement of said element and thereafter rotation of said element with said hand wheel, and means actuated by the axial movement of said element for disestablishing the driving connection between said shaft and said gear.

EDWARD J. FITZ.
